ALEXANDER CUNNINGHAM, OF BROOKLYN, NEW YORK, ASSIGNOR OF ONE-HALF TO
ALL AMERICA CABLES, INC., OF NEW YORK, N. Y., A CORPORATION OF NEW YORK.

COUPLING OF ELECTRICAL CIRCUIT.

Application filed August 22, 1923. Serial No. 658,690.

This invention relates to an improved method and apparatus adapted for use in electric signalling, and more particularly in some of its details to improvements in receiving instruments for telegraphs, such as are ordinarily employed when the signalling currents are very feeble, as in submarine work.

It is an object of the invention to provide an improved method and apparatus of the class mentioned for amplifying the effects of feeble currents and reproducing them in amplified form in a plurality of translating devices while at the same time avoiding interference or disturbance of one translating device upon another.

A further object is to provide an improved method and apparatus of the class mentioned for receiving the currents of a signalling system and to relay them in amplified form, and at the same time to make a record in amplified form of the signal as received, in such a manner as to avoid distortion in the relay and recorder circuits and to avoid mutual interference of these instruments.

Still another object of the invention is to provide an improved apparatus of the class mentioned whereby faults are more readily located and continuity of service thus promoted.

A further object is the provision of an improved apparatus of the class mentioned, whereby a plurality of translating devices may be operated in the receiver of the signal circuit without mutual interference with their operation or distortion of their circuits.

Other objects of the invention will in part be obvious and will in part appear hereinafter.

The invention accordingly comprises the several steps and the relation and order of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

For a complete understanding of the nature and objects of the invention, reference should be had to the following detailed description taken in connection with the accompanying drawings in which

Fig. 1 is a partially diagrammatic fragmentary view of a receiving apparatus embodying the invention; 55

Fig. 2 is a circuit diagram illustrating the application of the principles of the invention; and 60

Figs. 3 and 4 are modified circuit diagrams.

Referring to the drawing for a detailed description of the illustrative embodiments of the invention there shown, a sensitive receiving instrument is indicated in Fig. 1, illustrating an application of the invention for receiving and reproducing in amplified form the effects produced by weak electric current impulses such as encountered in submarine telegraphy. The sensitive receiving coil 9 is supported in the magnetic field of the field magnets N and S by a filament 10 for angular movement on its vertical axis in a known manner. The movable coil 9 is connected to the cable circuit by conductors 11, 12. 70

A light cradle plate 13 is suspended by a horizontally disposed thread or wire 14 supported at its ends by pins 15 and 16 adjustably mounted in a stationary yoke 17. The movable coil 9 is connected to transmit angular movement to the cradle plate 13 about its horizontal axis by means of fibres 18 connected to the upper and lower edges 85 of the cradle plate and to the coil 9.

Fine resistance conductors *a* and *b* are supported by the cradle plate by means of a light rod, preferably a hollow glass rod 19 attached to the cradle plate, depending therebelow and movable therewith. A conductor 20 is connected to the adjacent ends of the resistance conductors *a* and *b*, preferably extending through the hollow rod and leading to the circuit by a conductor indicated at 21. 90 As shown it is convenient to form the resistance conductors *a* and *b* of a continuous filament, the conductor 20 being electrically connected intermediate the ends thereof.

Fine resistance conductors *c*, *d*, similar to resistance conductors *a*, *b* are mounted in stationary position alongside of and parallel respectively to the conductors *a* and *b*, being however preferably mounted for independent adjustment so as to bring them into correct relative position with reference to the conductors *a* and *b*. Connecting conductors 22, 23 lead from the outer ends respectively 100 105

of the conductors *a* and *b*, and similar connecting conductors 24 and 25 are connected respectively to the outer ends of the conductors *c* and *d*. The connecting conductors 22, 23 in practice are to be arranged so as not to interfere with the free movement of the movable resistance conductors *a* and *b*, and the outer ends of the movable conductors *a* and *b* will be appropriately supported, as will be understood by those skilled in the art. The resistance conductors *a*, *b*, *c*, *d* are preferably of Wallaston wire, and when the apparatus is in operation are continuously heated by passage of an electric current, as will be more fully set forth hereinafter.

A preferred arrangement for the heated resistance conductors *a*, *b*, *c*, *d*, is indicated in the circuit diagram of Fig. 2. The movable conductors *a*, *b* are connected to form two arms of a Wheatstone bridge, the other two or balancing arms of the bridge being formed by resistances 26 and 27, one or both of which may be adjustable for initially balancing the bridge. A sensitive translating device 28 such as the coil of a relay of known construction is connected across the bridge between the juncture of arms *a*, *b* and the juncture of arms 26, 27. The heated resistance conductors *c*, *d*, similarly form two arms of a separate Wheatstone bridge, the remaining or balancing arms being formed by resistances 29, 30 which as in the case of balancing resistances 26 and 27 may be adjustable for initially balancing the bridge.

A second translating device 31, such as the sensitive coil of a recording instrument, is connected across the second bridge between the juncture of resistance conductors *c*, *d* and the juncture of balancing coils 29, 30. The resistance conductors *a*, *b*, *c*, *d*, are heated to the desired operating temperature by an electric current supplied by a source *E*, regulated by an adjustable resistance 32, an ammeter 33 being preferably employed to indicate the heating current. Also as shown in the embodiment of Fig. 2 the two bridges are connected for current supply from the battery *E*.

The operation of the apparatus above described is substantially as follows: The small angular movements of the coil 9 under the influence of the signal currents will be transmitted through the connecting fibres 18 to the cradle plate 13 which moves on its support 14 as an axis and through the supporting rod 19 transmitting lateral movements to the resistance conductors *a* and *b* corresponding to the movements of the coil 9. Movement of the cradle in one direction, for example, will bring the conductor *a* closer to conductor *c*, while the conductors *b* and *d* will at the same time be separated, while movement in the opposite direction will have the reverse effect, that is, conductors *a*, *c*, will be separated and conductors

b, *d* will approach each other, as will be clearly seen in Fig. 1. Since all these resistance conductors are continuously heated by the heating current, the mutual heat exchange between conductors *a* and *c* will be increased when the conductors are moved closer together, and radiation of heat from the wires into the surrounding air will be increased. Mutual heat exchange will be decreased when the conductors move apart. The conductors *b* and *d* will, of course, at the same time be subjected to similar effects of heat radiation and heat exchange, but conditions will be reversed, because when the space between the conductors *a* and *c* is decreased or increased the space between conductors *b* and *d* will be increased or decreased, respectively. It will therefore be seen that the conductors *a* and *c* will simultaneously increase in temperature to the same degree when spaced close together, and will simultaneously decrease in temperature to the same degree when spaced farther apart, and corresponding but reverse conditions will at the same time exist as regards the conductors *b* and *d*.

These mutual heating conditions of the resistance conductors are taken advantage of to unbalance the bridges due to the rise or fall of resistance when the temperature changes, and currents will flow through the translating devices 28 and 31, producing effects therein corresponding to the effects produced in the coil 9, but in amplified form. Current variations in the translating device 28 of the bridge having the movable resistance conductors will, therefore, be exactly duplicated in the translating device 31 of the other bridge, but there will be no interference of one bridge circuit by the other and no distortion will be produced in the circuits of the translating devices and consequently no interference with the continuous and satisfactory operation thereof. Each translating device exhibits the same manifestations as the other while they are connected in entirely separate electric circuits.

This arrangement is especially advantageous in telegraphy, particularly in submarine telegraphy, in which case the translating device 28 may be the electro-responsive or sensitive element of a relay instrument, while the translating device 31 may be the electro-responsive or sensitive element of a recording instrument. Since there is no distortion in the circuits of the sensitive elements and no mutual interference therebetween, the recording instrument will make a true record of the signals as received while the relay element 28 will independently perform its function. A disturbance in the relaying circuits or apparatus, will, therefore, not affect the operation of the recording mechanism, and line faults may therefore be more readily located and corrected. It will

be readily understood that the principles involved in this invention may be employed to reproduce, amplify, transmit, record or relay the effects of various feeble forces not being limited to the illustrative embodiment of the invention as set forth.

In the modified circuit diagram of Fig. 3 the arrangement of the heated resistance conductors and of the heat coupled Wheatstone bridges, is similar to that described in connection with Fig. 2 and the corresponding parts are indicated by the same reference numerals. The operation will be understood in view of the foregoing description. In this case, however, an ammeter 34 is employed in the circuit of the heated resistance conductors of each bridge and separate controlling resistances 35 are employed. It will, therefore, be possible by this arrangement to independently adjust the temperature of the resistance conductors of the bridges.

Also in the circuit arrangement disclosed in the embodiment of Fig. 4 the arrangement of heated resistance conductors and of heat coupled Wheatstone bridges is similar to that of Figs. 2 and 3, and the corresponding parts are indicated by the same reference numerals. In this case, however, two separate sources of energy of E' and E^2 are employed and the current from each source to the respective bridge is independently controlled through the adjustable resistances 35. In this case there is no electrical connection between the two Wheatstone bridges.

Since certain changes in carrying out the above process and in the constructions set forth, which embody the invention may be made without departing from its scope, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A method of amplifying and reproducing the effects of small forces in a plurality of translating devices which comprises connecting said translating devices in separate electric circuits, passing independent electric currents through said circuits so as to generate heat in each circuit, and reproducing in one of said translating devices by the mutual heat exchange between said circuits the effects produced in another of said translating devices by said small forces.

2. A method of amplifying and reproducing the effects of small forces in a plurality of translating devices which includes, connecting said translating devices in separate electric circuits, passing heating electric currents through said circuits so as to generate heat in parts thereof, effecting relative movement of said heated parts under the influence of said small forces to vary the mutual heat exchange between said heated parts, thereby affecting one of said translating devices in accordance with said small forces, and reproducing in another of said translating devices by said varying mutual heating effect the effect produced in said one translating device.

3. A method of amplifying and reproducing the effects of small forces in a plurality of translating devices which includes, connecting said translating devices in separate electric circuits, passing heating electric currents through said circuits so as to generate heat in parts thereof, changing under the influence of said small forces the heat generated in one of said circuits, thereby affecting one of said translating devices in accordance with said small forces, and reproducing in another of said translating devices, by the heating effect of one of said circuits on another, the effect produced in said first translating device.

4. A method of recording and concurrently relaying signals of a signal system including a recording device having a sensitive element and a relay having a sensitive element, which includes, connecting the sensitive element of the recording device and the sensitive element of the relay in separate electric circuits arranged in heat transferring relation, passing heating electric currents through said circuits, effecting relative movement of said circuits under the influence of said small forces to vary the heating of one of said circuits, and thereby affecting one of said sensitive elements in accordance with said small forces, and reproducing in another of said sensitive elements, by the heating transferring effect of one of said circuits upon another, the effect produced in said first sensitive element.

5. A method of recording and concurrently relaying signals of a signal system including a recording device having a sensitive element and a relay having a sensitive element, which includes, connecting the sensitive element of the recording device and the sensitive element of the relay in separate electric circuits arranged in mutual heat transferring relation, passing heating electric currents through said circuits, changing under the influence of the signals of said signaling system the mutual heat transferring effect of said circuits, thereby affecting one of said sensitive elements in accordance with said small forces, and reproducing in another of said sensitive elements by said

115
120
125
130

varying mutual heat transferring effect the effect produced in said first sensitive element.

6. A method of amplifying and reproducing the effects of small forces in a plurality of translating devices which includes connecting said translating devices in separate electric circuits, passing independent electric currents through said circuits so as to generate heat in the same, and thermally coupling said circuits so current variations in one translating device are reproduced in the other translating device through mutual heating effect of said circuits.

7. A method of reproducing the effects of feeble forces which includes utilizing the mutual heat exchange between two electric circuits to vary the currents carried by said circuits, varying said mutual heat exchange under the influence of the said forces to effect variations in the currents of said circuits in accordance with said forces and reproducing in amplified form in each of said circuits the effects of said forces.

8. In a signaling system, in combination, a receiver having a recording circuit and a separate relay circuit, a sensitive recording element connected in said recording circuit, a sensitive relay element connected in said relay circuit, a receiving circuit and means including a thermo-electric coupling for reproducing the effects of said receiving circuit simultaneously in said recording circuit and said relay circuit.

9. In a signaling system, in combination, a receiver having a plurality of circuits each including a heated resistance conductor, said resistance conductors being arranged for heat transference from one conductor to another, translating elements connected respectively in said circuits, means for actuating one of said translating elements under control of the received signal and means for correspondingly controlling actuation of another of said translating devices through heat transference between the heated resistance conductors.

10. In a signaling system, in combination, a receiver having a plurality of separate circuits each including a current heated resistance conductor, said conductors being arranged for heat transference from one to another, translating devices connected respectively in said circuits, means for effecting one of said translating devices in accordance with the received signal, means for effecting another of said translating devices through heat transference between the heated resistance conductors, and means for adjusting the current in said resistance conductors to vary the temperature thereof.

11. In a signaling system, in combination, a receiver having a plurality of circuits each connected in bridge formation, a translating device connected in each of said circuits, means for unbalancing one of said bridges

and thereby affecting its translating device in accordance with the received signals and means for coupling to the first bridge another bridge so as to affect its translating device in accordance with the received signal. 70

12. In a signaling system, in combination, a receiver having two circuits each connected in bridge formation, an electroresponsive device connected in each of said circuits, means for unbalancing one of said bridges and thereby affecting its electroresponsive device in accordance with the received signals, and a thermal coupling between said bridges to unbalance the second bridge and thereby affect its electroresponsive device in accordance with the received signals. 75

13. In a signal system, in combination, a receiver having two electric circuits each connected in bridge formation, a sensitive element of a relay device connected in one of said bridge circuits, a sensitive element of a recording device connected in the other of said bridge circuits, means for unbalancing one of said bridge circuits and thereby affecting its sensitive element in accordance with the received signals, a heat coupling between said bridges to unbalance the second bridge and thereby to affect its sensitive element in accordance with the received signals. 80

14. In a signal system, in combination, a receiver having two circuits each connected in bridge formation and each having a resistance conductor, an electroresponsive element connected in each of said bridge circuits, means for varying the temperature of the resistance conductor in one bridge to unbalance the same and thereby actuate its electroresponsive element under control of the received signals, and means for unbalancing the second bridge in accordance with the unbalancing of the first to control actuation of its electroresponsive element in accordance with the received signals. 85

15. In a signal system, in combination, a receiver having two circuits each connected in bridge formation and each having a resistance conductor, a sensitive element of a relay device connected in one of said bridge circuits, a sensitive element of a recording device connected in another of said bridge circuits, means for varying the temperature of the resistance conductor in one bridge to unbalance the same and thereby actuate its sensitive element under control of the received signals, and means for unbalancing the second bridge through heat transference to its resistance conductor from the resistance conductor of the first bridge to control actuation of its sensitive element in accordance with the received signals. 90

16. In a signal system, in combination, a receiver having a plurality of circuits each having a resistance conductor, a sensitive element of a relay device connected in one 120

circuit, a sensitive element or recording device connected in another circuit, means for varying the temperature of the resistance conductor in one circuit to thereby actuate its sensitive element under control of the received signals, and means for controlling actuation of the sensitive element of another of said circuits in accordance with the received signals by heat transference between said resistance conductors.

17. In a signaling system, in combination, a plurality of independent bridge devices having translating elements, and means for thermally coupling said translating elements whereby variations in the current traversing one element is reproduced in another element without electrical distortion.

18. A plurality of Wheatstone bridges thermally coupled whereby the unbalancing of one bridge is reproduced in another by virtue of the thermal coupling.

19. In a signalling system, in combination, a plurality of circuits arranged in bridge formation, a translating device connected across each bridge, one of said bridges having an arm so mounted that its physical relation to the other bridge may be altered to make simultaneous and corresponding alterations in both bridge circuits.

20. In a signalling system, in combination, a plurality of circuits each arranged in bridge formation, each including a translating device, means whereby one of the arms of one bridge may have its physical relation to the corresponding arm of the other bridge altered to simultaneously unbalance both bridges, said circuits being so arranged that their balances are independent of said translating devices.

21. In a signaling system, in combination, a plurality of circuits each arranged in bridge formation, an additional or actuating circuit, and means controlled by said actuating circuit to simultaneously and proportionately unbalance both bridges thereby to reproduce therein electrical variations in

accordance with electrical variations taking place in said actuating circuit.

22. In a signalling system, in combination, a plurality of circuits each arranged in bridge formation, said bridge circuits each having two arms independent of the other bridge and two arms mutually related to said other bridge whereby movement of certain of said mutually related arms relative to said others simultaneously and proportionately unbalances both bridges.

23. In a signaling system, in combination, a bridge circuit having a translating device and a resistance conductor in one of the bridge arms thereof, a signal circuit, a heating element mounted adjacent to said resistance conductor, and means controlled by said signal circuit for varying the heat effect of said heated element upon said resistance conductor.

24. In a signaling system, in combination, a plurality of bridge circuits each having a translating device connected therein and each having a resistance conductor in one of its bridge arms, means to heat said resistance conductors, said resistance conductors being mounted adjacent each other so as to vary their temperature by mutual heat exchange, a signal circuit, and means controlled by said signal circuit for varying the mutual heating effect of said resistance conductors upon each other.

25. In a signaling system, in combination, a plurality of circuits each arranged in bridge formation and including electro-sensitive translating devices, an additional or actuating circuit, bridge coupling means included in said bridge circuits, and means whereby said actuating circuit controls said coupling to simultaneously unbalance both bridges thereby to reproduce in each of said translating devices electric variations in accordance with variations taking place in said actuating circuit.

In testimony whereof I affix my signature.
A. CUNNINGHAM.
